DIAL TIMING MECHANISM FOR CIRCULAR
KNITTING MACHINES

Roland J. Paquette, Woodstock, Ontario, Canada,
assignor to Scott & Williams, Incorporated,
New York, N. Y., a corporation of Massachusetts

Application October 9, 1935, Serial No. 44,257

12 Claims.

(Cl. 66—28)

This invention relates to revolving needle cylinder circular knitting machines containing two series of knitting elements, i. e., needles or needle cooperating elements, and more particularly to the mechanism by which the second element such as the dial is kept in time, i. e., proper alignment, with the needle cylinder.

In circular knitting machines adapted to make rib fabric or containing a dial with other knitting elements in it, the dial is adapted to be swung pivotally upward out of operative position for repair, replacement of parts and observation. It is necessary that the knitting elements in the dial and cylinder be kept in accurate alignment with each other even when the dial is raised, in order that trouble may be avoided when the dial is swung down into operative position again and the machine is started. One of the objects of the invention is to produce a simple, durable and convenient mechanism for insuring that the dial is always put back into operative position with its elements in proper mesh and alignment with the elements in the needle cylinder. It is characteristic of a machine made in accordance with the invention that there is a connection between the dial and cylinder which keeps the two in accurate alignment when the dial is raised to inoperative position, but this connection does not drive the dial when the machine is knitting. With this construction the dial and cylinder are always in mesh by means of a flexible connection, but the dial can be disconnected readily in order to turn it by hand. The invention will be shown embodied in the well-known Scott & Williams revolving needle cylinder type of machine such as shown in the patent to Robert W. Scott No. 1,282,938, dated October 29, 1918.

Referring now to the drawings,

Fig. 1 is a front view, partly in section, of part of the head of a Scott & Williams revolving needle cylinder knitting machine, showing the dial-driving clutch engaged and the dial in its operative position;

Fig. 2 is a view in elevation of the clutch and flexible connection, with the clutch parts disengaged;

Fig. 3 is an inverted plan view, looking at the upper part of the clutch, taken on the line 3—3 of Fig. 2;

Fig. 4 is a plan view of the lower part of the same clutch, taken on the line 4—4 of Fig. 2;

Fig. 5 is a detail view on an enlarged scale showing the intermeshing of the transfer bits, cylinder needles and sinkers when the dial is in

its operative position, the view being taken in radial section through the edge of the dial;

Fig. 6 is a view in elevation from the right side of the machine, partly broken away, with the dial in its raised or inoperative position, the 5 dotted position of the flexible member showing its position when the dial is disconnected from the cylinder;

Fig. 7 is a detail view of the flexible member of Figs. 1 and 6, broken away to show its construction;

Fig. 8 is a view similar to Fig. 1, omitting the cylinder and dial but showing a preferred embodiment;

Fig. 9 is a view in elevation similar to Fig. 8, 15 showing the modified construction with the clutch disengaged;

Fig. 10 is a view in elevation of the right side of the modification of Fig. 8, showing sufficient of the machine to illustrate the position of the 20 parts of the novel mechanism when the dial is raised to its inoperative position;

Fig. 11 is an inverted plan view showing the upper member of the clutch of Fig. 8, taken on the line 11—11 of Fig. 9;

Fig. 12 is a plan view taken on the line 12—12 of Fig. 9, similar to Fig. 11 but showing the entire lower clutch element;

Fig. 13 is a detail view showing the male member of the clutch and the manner in which the 30 flexible member is fastened thereto; while

Fig. 14 is an enlarged sectional view of the sleeve at the lower end of the flexible member and how it is attached to the flexible member, this view being in section.

In revolving needle cylinder machines containing dials with knitting elements therein, care has to be taken to mesh the dial properly when lowering the latch ring in order to avoid breaking or damaging the cylinder needles, dial needles or 40 the transfer jacks. If at certain stages in the knitting the dial is out of register sufficiently to bring the high or long butt needles on the wrong side, care is necessary to avoid breakage or damage to the cams or levers operating the dial parts. 45 It has heretofore been known to keep the dial and cylinder continuously connected or in alignment, even when the dial is raised to its inoperative position, by means of two universal joints forming a drive, such for instance as shown in 50 the patent to Albert E. Page and Harry Swinglehurst, Jr., No. 1,906,204, dated April 25, 1933. In this case the drive at all times is through the universal joint drive and its joints wear quickly. It has also been found that this universal joint 55

drive has a tendency to gain or lose slightly. This form of drive also is expensive, complicated and unwieldy. It is a device which in itself has to be kept in alignment. It also has the disadvantage that the dial must revolve while it is being raised to the inoperative position. This turning is apt to cause damage to the needles and jacks when the dial is lifted during the time that the dial elements are protruding between the needles, and further makes it necessary for the operator to reposition more of the dial elements than is necessary merely because of the pivotal mounting of the dial.

In the drawings I have illustrated, and in the specification I will describe, the invention embodied in a Scott & Williams machine which uses transfer bits or jacks in the dial, but it should be understood that the invention is equally applicable to machines which have other knitting elements in the dial. The invention is applicable to any circular machine in which it is important to keep two series of knitting elements in alignment with each other while breaking the gear drive of one of the two element-carrying members.

The embodiment of the invention shown in Figs. 1 to 7 will be described first. The machine has the usual revolving needle cylinder 260 carried by the bedplate B and driven from the main drive shaft (not shown) by the usual gears 30, 31 (see Fig. 1). The usual latch needles N are moved vertically in slots on the outside of the needle cylinder 260 by the cams associated with the stationary cam ring 271. The usual sinkers 35 or web holders 292 are supported on the upper end of the needle cylinder 260 by the inside sinker ring or nosing 297 and the outside sinker ring 295. These webholders are reciprocated radially in the usual manner by the sinker cap 300. As shown in dotted lines in Fig. 6, the latch ring 550 is supported from the customary latch ring bracket 401 mounted on the bedplate B. This pivotal point of the latch ring is at the rear of the machine, so that when the latch ring 45 is swung up into inoperative position, it swings upward and backward. Mounted on the latch ring is a dial-supporting bracket 14 (see Fig. 1). The dial D carrying the transfer bits T is carried on a vertical spindle 3 supported in this 50 bracket 14.

The means for driving the dial D when the same is lowered into operative relation with the needle cylinder and its knitting elements will now be described. The members supported by the 55 dial-carrying bracket 14 are mostly of known construction. Fastened on the dial-carrying spindle 3 is a horizontal bevel gear 15 meshing with a pinion 16 carried on the radially central end of a horizontal dial-driving shaft 17. This 60 shaft 17 is carried in two bearings forming part of the bracket 14 and has a vertical bevel gear 18 mounted on its outer end. There is a gear casing or cover 24 carried by the bracket 14 covering these gears and also having an additional function.

The power to drive the vertical bevel gear 18 is obtained from the main drive shaft by means of bevel gear 64 and horizontal pinion 63 meshing therewith, acting through the following 70 novel elements. The pinion 63 is mounted on the lower end of a vertical spindle 10 which is supported in a bearing bracket 11 mounted on the bedplate B of the machine. Customarily the pinion or gear meshing with the vertical bevel 75 gear 18 would be mounted fixedly on the upper

end of the spindle 10. In such a standard construction, when the latch ring and dial are swung back to inoperative position by pivoting about its axis on the bracket 401, the bevel gear 18 and associated pinion become disengaged from each other, thus breaking the chain of gears between the needle cylinder and the dial. This necessitates mechanism such for instance as that shown in the patent to Robert W. Scott No. 1,356,092, dated October 19, 1920.

According to my invention, there is a pinion 19 carried by an extension of the gear cover 24 which is always in mesh with the vertical bevel gear 18 and is lifted up and down with the dial on the latch ring bracket. This pinion 19 is carried by means of a yoke 50 mounted on the gear cover 24, taking into a groove 51 on the stub of the pinion 19. It is held on the upper side by a washer and a screw 52 (see Fig. 7). Between this pinion 19 and the vertical spindle 10, I introduce 20 a clutch. One part or member of this clutch is 25 unitary with the pinion 19 and therefore moves away from its mate when the dial is raised to inoperative position, while the other member of the clutch is formed on the upper end of the 30 spindle 10. In the form of the invention shown in Figs. 1 to 7, it is a female member 28 which is 35 formed out of the same piece of metal as pinion 19 and it is the male member 27 which is formed on the upper end of the spindle 10. In the particular embodiment shown in these figures, the female member 28 has two recesses with a fin or blade between and the male member has two blades to go into those recesses. As can be seen clearly in Fig. 2, the male member 27 is preferably made with the ends of its blades tapered or bevelled at 29. The purpose of these bevelled edges is to guide the parts into accurate alignment when the two parts of the clutch are brought together. Thus if for any reason the female 40 member should get slightly out of line with the male member, the bevelled surfaces will bring it back into accurate registry as the two parts engage. There is the usual latch and pin device 45 53 attached on the gear cover 24, and the upper part of the bearing bracket 11 to insure that the latch ring bracket is not accidentally displaced. The vertical spindle 10 is maintained at the proper elevation by a set screw 55 in a ring 54 fastened on the upper end of the spindle just 50 below the clutch member 29 and resting on the upper end of the bearing bracket 11 (see Figs. 1 and 2).

In combination with this novel clutch arrangement, I incorporate a timing connection between 55 the needle cylinder and the dial which insures that the dial is always kept in correct alignment with the cylinder while the dial is in inoperative position, i. e., at all times when the two parts 27, 28 of the clutch are disengaged. This timing 60 connection is a flexible one between the two parts 27, 28 of the clutch and is a telescopic construction which in effect keeps the gears in mesh. This connection includes a flexible member or cable 40 with one end fastened rigidly to one of the parts of the clutch and the other end having on it a key or slide 41 adapted to move through the other part of the clutch and thus provide the telescopic feature but not permit turning of 70 the cable with relation to this second part of the clutch. In the drawings it is the upper end of the cable 40 which is shown fixed rigidly in the piece of metal constituting the female part 28 of the clutch and the pinion 19. The cable 75

should be soldered or otherwise fixed tightly in the clutch part 28.

As can be seen in Figs. 7 and 14 of the drawings, the cable consists essentially of three layers 5 of counter-wound wire 56, preferably wound on a core of a straight single wire 57. These counter-windings are each tensioned properly so that it is practically impossible to twist the cable. The cable is flexible, in spite of the fact that it 10 resists any attempt to twist it. In Fig. 14 is shown the manner in which the lower end of the cable is fastened in its slide or key 41. This slide or key 41 is preferably shaped in a square but can be made in any shape which cannot be 15 turned when placed in a complementary opening.

It will be observed from the drawings that I prefer to locate the cable axially central of the driving spindle 10 and the clutch members 27, 28 and the pinion 19, and that the size of the cable 20 is such that it lies between the two recesses 58 in the female part 28 of the clutch and is no greater in diameter than the fin between those two recesses 58. The shape of the recesses can be seen in Fig. 3 on either side of the central pin. To 25 make possible this telescopic feature, the driving spindle 10 is hollowed out with a square central opening 59 throughout its length, as can be seen in Figs. 1 and 6. It is just the size or shape of the slide 41 and permits movement of the latter 30 without any substantial play. In the embodiment shown in the drawings, this recess 59 does not extend quite to the bottom of the spindle 10, but this can be as short or as long as desired. In this connection, if desired, the lower end of 35 the recess 59 in the spindle 10 can be made slightly larger so that the key 41 will have a certain amount of play as added insurance that the cable and associated parts will not be under any strain until the dial starts to lift. As shown in 40 Fig. 14, the lower end of the cable 40 is soldered into the slide 41 so that the end is held rigidly in the slide, and since the slide cannot turn it follows that the cable cannot turn. Since the lower end of the cable is unable to turn, it follows 45 that it is impossible for the dial to get out of register or alignment with the cylinder while the clutch 27, 28 is disengaged. In this way it will be noted that I have provided a flexible connection between the two parts of the clutch which 50 will keep the dial and cylinder and their knitting elements in register whenever these parts of the clutch are disengaged, and in this way the dial and cylinder can be said to be always in mesh. It will be observed that by having a flexible connection there is no strain on associated parts, and further that when the two parts of the clutch 55 are in engagement, it is they and not the flexible connection which do the driving. In other words, this connection has the novel feature of not being involved in any way in the drive of 60 the machine when the gears are in mesh. There is no wear and tear on the mechanism which keeps the dial and cylinder in alignment when the regular driving means are disconnected, and 65 therefore no chance for the mechanism to wear and eventually get out of alignment.

This mechanism has an added advantage in the fact that when the dial is being raised from operative to inoperative position, the dial is not 70 being turned. Heretofore in all devices which maintain driving connection between the cylinder and dial while the dial is being raised to inoperative position, the dial has had to turn while being raised. This is due to the fact that 75 the regular driving gears are maintained in oper-

ative relation. In my novel mechanism the gears do not turn but are held without turning on their own axes while they are disengaged, so that the dial does not turn while being raised.

It is sometimes desirable to turn the dial by 5 hand while it is in its raised position in order to make repairs or adjustments. This can be accomplished very simply on my device without the use of any tools. To this end it will be noted that I have made the recess 59 in the driving 10 spindle 10 of the same cross section extending through the male member 27 of the clutch (see Figs. 4 and 6). By these means it is perfectly simple for the operator to pull the cable up and set the key end of the cable free as shown by the 15 dotted line position in Fig. 6. It is then possible for the dial to be turned freely by hand as much as desired. By having this key 41 square, it is obvious that if the dial is brought back approximately into its proper registry in order to get 20 the key 41 back into the recess 59, the dial will be brought into proper register. If desired, this advantage of the shape of the key 41 can be further extended by making the key irregular in shape. 25

I will now describe the preferred embodiment which is shown in Figs. 8 to 13 of the drawings. In this embodiment the parts show greater adaptability to their uses and improved ability to take care of wear and tear. The members or parts 30 of the clutch have been changed but the spindle 10, bearing bracket 11, the cable 40 and the key 41 remain the same. Instead of using a collar 54 and set screw 55 to hold the spindle 10 to the proper elevation to provide accurate meshing of the parts of the clutch, the upper end of the spindle is enlarged to provide its own resting shoulder, as shown at 66 in Fig. 10. In the case of the embodiment shown in Figs. 8 to 13, the male member is the upper portion of the 40 clutch and is carried with the dial. It is designated by the reference character 71 and is carried on a shaft 74 on which the pinion 72, which meshes with the bevel gear 18, is carried. The upper end of the cable 40 is set in the lower end 45 of this shaft 74. The male member consists of a sleeve or shell having two downwardly projecting ears 73 which lie partly below the lower end of the shaft 74, the sleeve being held on the lower end of the shaft by a set screw, as shown 50 in Fig. 13. The female member 68 of the clutch is formed out of the upper end of the hollow spindle 10 and has a shoulder 66 overlying the upper end of the bracket 11. The upper face of the female member 68 has two grooves 69 in 55 it radiating from the center and adapted to receive the downwardly depending ears 73 of the male member 71. The lower end 99 of the shaft 74 projects slightly below the shell carrying the ears 73 and sits in a recess 69a in the female 60 member. This insures the two parts of the clutch being lined up properly. The ears 73 are spaced apart such a distance that their outer edges correspond to the outer edges of the female member. The semi-circular stubs 67 which define the 65 grooves 69 of the female member 68 extend radially outward as far as the shoulder 66. The pinion 72 of the male member 71 can be supported by an arm 78 depending from the gear cover 24. The shaft 74 extends above the pinion 72 and is supported at that point by a yoke 79 in somewhat the same manner as in the previous embodiment. To insure that the pinion 72 and male member 71 of the clutch are properly centered over the 70 spindle 10, a pointed set screw 95 is mounted 75

point upward on the upper end of the bearing bracket 11 just to one side of the female member 68 of the clutch. This pointed set screw is adjusted to take into the complementary recess 96 in the lower face of the arm 78 of the gear cover 24. This supplements the latch and pin 53 found in the previous embodiment.

If, by any chance, in the course of time a slight amount of torsion develops in the cable 40, which would be too great to be taken care of by the bevel surfaces 29 of the embodiment of Figs. 1 to 8, longer bevels are provided in the embodiment of Figs. 9 to 13. This feature takes the form of a bevelled shield 97 located on the circumference of the female member 68 and projecting upwardly above the ears 67 (see Figs. 8, 9 and 12). This plate is bevelled at a corner leading to one of the slots 67. On the periphery of the male member 71 at a point directly opposite the ear 73 which should register in the groove 69 adjacent the shield 97, is a set screw 98 projecting into the path of the bevelled edge of the shield 97. As the two members of the clutch start to come together, if there is a slight torsion in the cable, or for any other reason the parts are not in accurate alignment, the set screw will overlie the shield as shown in Fig. 9. This set screw 98 will ride down the bevelled edge of the shield 97 and will thus bring its ear 73 into the groove 69 intended for it, as shown in Fig. 8.

It will be obvious that the new functions attained by my invention are reached with the minimum number of parts and with a simplicity 35 and economy which recommend themselves to the practical man. It will be obvious that with my mechanism the transfer bits T or the needles in the dial will always be kept in proper register with the cylinder needles N, no matter in what 40 position the dial may be put and whether or not the machine turns in either direction while the dial is up. It is a distinctive feature that the clutch and the mechanism which controls the position of the dial when raised are alternate- 45 drives each idle while the other works, and therefore not subject to wear and tear, when the machine is actually knitting.

Many modifications which do not depart from the scope of the invention will occur to those 50 skilled in the art. Thus the connection between the cable 40 and the upper part of the clutch can be telescopic in place of that at the lower part or in addition to that at the lower part. The cable 40 need not necessarily pass through the 55 axis of revolution of the clutch parts but can be beside them as long as they are geared to the two parts of the drive.

What I claim is:

1. In a circular knitting machine, two series of 60 knitting elements, a revolving cylinder containing one of said series and a dial containing the other and adapted to be moved into and out of operative relation with the cylinder, in combination with means adapted to drive the dial when 65 the latter is in its operative position only, and a connection between the dial and its driving means operative when the dial is moved from operative position to keep the latter in time with the cylinder.

2. In a circular knitting machine, two series of 70 knitting elements, a revolving cylinder containing one of said series of elements and a dial containing the other series and adapted to be moved into and out of operative relation with the cylinder, in combination with a clutch adapted to keep the dial in time with the cylinder.

to drive said dial in timed operative relation with the cylinder, and a flexible torsion-resisting connection for said dial operative upon disengagement of said clutch to keep the dial in time with the cylinder.

3. In a circular knitting machine, two series of 10 knitting elements, a revolving cylinder containing one of said series and a dial containing the other and adapted to be moved into and out of operative relation with the cylinder, in combination with a gear train driving said dial and cylinder in 15 timed relation, including a clutch adapted to be disconnected when the dial moves out of operative relation with the cylinder and a flexible torsion-resisting connection adapted to keep the dial and cylinder knitting elements in proper timed relation when the gear train is disconnected.

4. In a circular knitting machine, two series of 20 cooperating knitting elements, a revolving cylinder containing one of said series and a dial containing the other and adapted to be swung into and out of operative relation with the cylinder, in combination with a clutch adapted to drive said dial and a flexible connection between the two parts of 25 said clutch adapted to keep the dial in time with the cylinder when the clutch is disengaged.

5. In a circular knitting machine, a revolving cylinder, a circle of needles therein, a pivotally mounted dial adapted to be swung into and out of operative relation with the cylinder, and needle 30 cooperating elements in said dial, in combination with a clutch adapted to drive said dial, and a telescopic connection including a flexible member 35 between the two parts of said clutch adapted to keep the dial in time with the cylinder when the clutch is disengaged.

6. In a circular knitting machine, a revolving cylinder, a circle of needles therein, a pivotally mounted dial adapted to be swung into and out of operative relation with the cylinder and needle 40 cooperating elements in said dial, in combination with a flexible connection between the two parts of said clutch, including a flexible member held at one end to turn in time with the needle cylinder 45 and at the other end in time with the dial, said flexible member having substantially no torsion, said connection being adapted to keep the dial in time with the cylinder when the clutch is disengaged.

7. In a circular knitting machine, a revolving cylinder, a circle of needles therein, a pivotally mounted dial adapted to be swung into and out of operative relation with the cylinder, and needle 55 cooperating elements in said dial, in combination with a clutch adapted to drive said dial, and a flexible connection between the two parts of said clutch, including a flexible member adapted to telescope through one part of said clutch, held at one end to turn with the needle cylinder and at 60 the other end with the dial, said flexible member having substantially no torsion, said connection being adapted to keep the dial in time with the cylinder when the clutch is disengaged.

8. In a circular knitting machine, two series 65 of cooperating knitting elements, a revolving cylinder containing one series and a dial containing the other and adapted to be swung into and out of operative relation with the cylinder, in combination with a clutch adapted to drive said dial, 70 the parts of said clutch including a bevelled surface adapted to guide the parts into axial alignment when the parts are coming into engagement, and a flexible connection between the two parts of said clutch adapted to keep the dial in 75

time with the cylinder when the clutch is disengaged.

9. In a circular knitting machine, two series of knitting elements, a revolving cylinder containing one series and a dial containing the other and adapted to be moved into and out of operative relation with the cylinder, a clutch adapted to drive said dial and to be disengaged when said dial moves out of operative relation with the cylinder, in combination with a flexible torsion-resisting connection between the parts of said clutch having a telescopic connection at one end, said telescopic connection fitting into a complementary recess preventing rotation of the end of said flexible member in the recess.

10. In a circular knitting machine, a revolving needle cylinder, a circle of needles therein, a pivotally mounted dial adapted to be swung into and out of operative relation with the cylinder, and needle cooperating elements in said dial, in combination with a clutch adapted to drive said dial and to become disengaged when the dial swings out of operative relation with the cylinder, and a flexible telescopic connection between the two parts of said clutch adapted to keep the dial in time with the cylinder when the clutch is disengaged, the parts of said clutch including a beveled surface and a projection adapted to guide the

parts into accurate alignment when they are coming together.

11. In a circular knitting machine, two series of knitting elements, a revolving cylinder containing one of said series and a dial containing the other and adapted to be moved into and out of operative relation with the cylinder, in combination with a gear train driving said dial and cylinder in timed relation, including a clutch adapted to be disconnected when the dial moves out of operative relation with the cylinder and a flexible torsion-resisting connection adapted to keep the dial from turning except with the cylinder while disconnected from the gear train.

12. In a circular knitting machine, two series of knitting elements, a revolving cylinder containing one of said series and a dial containing the other and adapted to be moved into and out of operative relation with the cylinder, in combination with two complementary driving means keeping the dial and cylinder in proper timed relation, one means including a clutch adapted to drive when the dial is in its operative position, and the other means including a flexible torsion-resisting member and effective when the dial is not in its operative position.

ROLAND J. PAQUETTE.
